Geo. G. Lyman
Assignee
Alexander Mower
Co.

United States Patent Office.

GEORGE G. LYMAN, OF INDEPENDENCE, IOWA, ASSIGNOR TO HIMSELF AND JOHN F. LYMAN, OF SAME PLACE.

Letters Patent No. 91,757, dated June 22, 1869.

IMPROVEMENT IN HARVESTERS.

The Schedule referred to in these Letters Patent and making part of the same.

To all whom it may concern :

Be it known that I, GEORGE G. LYMAN, of Independence, in the county of Buchanan, and in the State of Iowa, have invented certain new and useful Improvements in Combined Reaper, Mower, and Corn-Cutter, and do hereby declare that the following is a full, clear, and exact description thereof, reference being had to the accompanying drawings, and to the letters of reference marked thereon.

My invention relates to an improvement on the harvester for which Letters Patent were granted to me, April 21, 1868, and consists—

First, in the vibrating levers and their connections with the pitman.

Second, in the manner and device for throwing said levers, &c., in and out of gear with the driving-wheel cams.

Third, in the driving power operating on said levers by roller-cams set on the inside of two driving-wheels instead of one, as in my former patent.

Fourth, in a new and independent method of raising the sickle-bars, by means of an eccentric lever working on a chain and pulley on a main frame, bringing all the bearings on the centre or axle of the machine.

In order to enable others skilled in the art to which my invention appertains, to make and use the same, I will now proceed to describe its construction and operation, referring to the annexed drawings, which form a part of this specification, and in which—

Figure 1 is a side elevation, and

Figure 2, a plan view of the machine.

Figure 3 is a side view of one of the driving-wheels with its roller-cams;

Figure 4 is a side view of the lever, by the use of which the vibrating levers are thrown in and out of gear; and

Figure 5 is a plan view of the front end of the machine, (with fig. 4 removed,) showing the front ends of the vibrating levers, with the carriage operating on the same, to throw them in and out of gear.

A represents a horizontal frame, attached at or near its centre to the axle B, which is provided with a driving-wheel, C, at each end outside of said frame. At the front end of the frame A is secured the tongue D.

From the axle B, just inside of the frame A, is suspended a box, E, the axle passing through the sides of said box at or near its centre, and to the rear end of said box the braces are attached.

For the purpose of raising or lowering the box E, a chain or rope, a, is attached to the front and rear end of said box, the chain passing up around pulleys b b, in the front and rear end of the frame A, and is, at a suitable point on said frame, attached to a lever, c, pivoted in a slot in the side of the frame A.

This lever c is acted upon below the frame A by an eccentric lever, d, so that by the action of said eccentric lever upon the lever c and chain a, the rear end of the box E may be raised or lowered at will.

On the shaft B, inside of the box E, are placed two smaller wheels F F, a suitable distance apart, and of such diameter that the outer rims of said wheels will be as close to the bottom of the box E as possible without touching the same.

The axle B, forming the centre, as well for the frame A as for the box E, it will be seen that it will make no difference what position the box E is in; the wheels F F will always be at the same distance from the bottom of the same.

Inside of the rims of the wheels F F, and on the inner side, is placed a series of rollers, e e, at equal distance apart, which rollers operate two vibrating levers G and G', placed on the bottom of the box E.

The rollers e e are, however, so placed in the wheels F F that each roller on one wheel is opposite the space between two rollers on the other.

In the centre of the bottom of the box E is placed a bar or slotted plate, which holds the two vibrating levers G and G' down to the said bottom, but allows a lateral or vibrating motion of the levers when operated upon by the rollers e e, the vibrating levers being for this purpose on their outer sides provided with a cam-shaped projection, as shown in dotted lines in fig. 2.

It will readily be understood that if, for instance, the front ends of the levers G and G' were kept a suitable distance apart, and the front ends of said levers had some yielding substance between them, then, if the machine was in motion, the rollers e e, operating upon the cam-projections alternately, would give the front ends a vibrating motion.

To effect this, I pivot the front end of the lever G in some suitable manner to the bottom of the box E, and against a cross-bar, H, placed a short distance from the front end of said box; this end of the lever G of course near or close to the side of the box.

The front end of the other lever, G', is made movable, so that it can be thrown in and out of gear at will. This is done by a lever, f, pivoted in a slot in the centre of the cross-bar H, one end of said lever extending in rear and the other in front of said cross-bar.

The end in rear of the cross-bar operates upon the front end of the lever G', while the other end enters a slot in the side of a carriage, I, placed between the front end of the box E and the cross-bar H, as seen in fig. 5.

One end of the carriage I is slotted, and provided with a pin, i, which is surrounded by the forked lower

end of a lever, *g*, said lever being pivoted in a slot on a board, *J*, which covers the front end of the box *E*, as seen in fig. 2.

It will be seen that by turning the lever *g* to one side, the carriage *I* is moved in such a manner as to cause the lever *f* to press the front end of the lever *G'* outwards, holding it in position to be acted upon by the rollers *e*.

The lever *g* is held by an arm, *h*, so as to cause the effect above described, as shown in fig. 4.

To throw the lever *G'* out of gear again, it is only necessary to release the arm *h*, when the vibrating motion of said lever will at once cause its front end to move inwards.

To the bar above mentioned, which holds the vibrating levers in the centre of the box *E*, is attached an arm, *k*, to the rear end of which is pivoted a connecting-link or arm, *m*.

This arm is, at a suitable point, provided with a circular projection, *n*, having a recess on each side, in which the rear ends of the vibrating levers *G' G'* operate, so as to cause the connecting-bar *m* to move rapidly from side to side.

On one side of the rear end of the box *E*, the arms *o o* extend a suitable distance, and to their outer ends the finger-bar *K* is attached in any of the known and usual ways.

The cutter-bar *L* receives the necessary motion from the connecting-bar *m*, through the pitman *p*, which is pivoted to the rear end of said connecting-bar.

The braces *o o* are connected with the under side of the frame *A* by means of a brace-bar, as seen in fig. 1. Having thus fully described my invention,

What I claim as new, and desire to secure by Letters Patent, is—

1. The arrangement of the vibrating levers *G G'* and pivoted connecting-link, or bar *M*, having a circular projection, *n*, with a recess on each side, in which the levers operate, substantially as shown and described.

2. The arrangement and combination of the vibrating levers *G G'*, lever *f*, carriage *I*, forked lever *g*, and arm *h*, all substantially as and for the purposes herein set forth.

3. The arrangement of two wheels on the axle of the machine, with rollers on the inside of said wheels, to operate the vibrating levers, substantially as and for the purposes herein set forth.

4. The arrangement of the eccentric lever *d*, lever *c*, and chain *a*, working on the main frame *A*, for the purpose of raising the sickle-bars, substantially as herein set forth.

In testimony that I claim the foregoing, I have hereunto set my hand, this 15th day of February, 1869.

GEORGE G. LYMAN.
